(57) **CLAIM**

The ornamental design for a towel bar as shown and described.

DESCRIPTION

FIG. 1 is a front perspective view of a towel bar showing our new design in a first configuration of use;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof, shown in a state of use with environment;

FIG. 10 is a front perspective view showing the towel bar in a second configuration of use;

FIG. 11 is a rear perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is a front perspective view thereof, shown in a state of use with environment.

Shading is used in the drawings to better illustrate the design. The broken lines depict environment and portions of the article that form no part of the claimed design. The towel bar is shown with a symbolic break in its length in both the horizontal member and the vertical member. The portion between the break lines forms no part of the claimed design.
